UNITED STATES PATENT OFFICE.

PHILIPP SUTER, OF BADEN, SWITZERLAND, ASSIGNOR TO AKTIENGESELLSCHAFT BROWN BOVERI & CIE., OF BADEN, SWITZERLAND, A JOINT STOCK COMPANY OF SWITZERLAND.

VENTILATING ROTOR CONSTRUCTION.

Application filed January 25, 1926, Serial No. 83,501, and in Germany January 30, 1925.

This invention relates to construction of rotors for electrical machines, particularly induction motors. It has to do primarily with the assembly of the rotor laminations in a fashion such as to afford them desired cooling ventilation.

The general purpose of the invention is the provision of a construction which will afford the laminations and their associated 10 windings the desired cooling ventilation, contribute to facility and economy of construction and preserve the integrity of the structure under trying operation.

Another object is the provision of such a 15 construction particularly adapted to machines designed for high speeds.

Another object is to preserve the proper alignment of the winding slots of the laminations.

20 Other and further objects will be pointed out hereinafter, indicated in the appended claims, or obvious to one skilled in the art upon an understanding of the present disclosure.

25 In the accompanying drawing forming a part of this specification I show one embodiment of the invention, but it is to be understood that the same is presented for 30 illustrative purposes only and is not to be given any construction limiting the invention claimed, short of its true and most comprehensive scope in the art.

In the drawing,

35 Fig. 1 is a part transverse sectional view of a construction embodying the invention,

Fig. 2 is a sectional detail on line 2—2 of Fig. 1 and

Fig. 3 is a sectional detail on line 3—3 of Fig. 1.

40 Referring to the drawing, let it be understood that the reference numeral 10 designates a portion of the spider of the rotor, which is suitably supported for rotation in a customary manner and affords an internal 45 air circulating space S. In the spider are carried the rings 11, shrunk onto the spider while heated and further secured against shifting by the keys 12. These rings are continuous about the spider and are spaced apart, as shown in Figs. 2 and 3, giving liberal space for radial movement of air between them. The spacing is preserved by the spacing pieces 14, which are secured to opposite sides of the alternate rings by the

rivets 15. The rings are formed with the 55 dove-tail projections 11^a, disposed in alignment longitudinally of the rotor, and the spacing pieces are likewise provided with the dove-tail projections 14^a, disposed in alignment and lateral contact with the projections 11^a. Thus continuous ribs of dove-tail section are formed longitudinally of the rotor. On these ribs are fitted the bundles 60 of laminations 16, the outermost laminations of adjacent bundles being spaced apart, over 65 the spaces between the associated rings 11, by suitable bosses or ribs 16^a, so as to preserve air circulating spaces between them. These air spaces between bunches of laminations preferably are somewhat narrower 70 than the spaces between the rings, for a purpose mentioned hereinafter. At the ends of the rotor the laminations are retained by suitable clamping rings 17, drawn up by 75 bolts 18. The laminations of the respective 80 bunches preferably are of sufficient length to effect engagement, by means of their dove-tail slots, with a plurality of the retaining ribs, and the laterally adjacent bunches are disposed in echelon or broken-joint relation- 85 ship, as indicated by the line e in Fig. 1, showing the end of the next rearward bunch. The laminations are notched to provide the slots 16^b for accommodation of the rotor 90 windings, the arrangement of the notches 85 being such that those of adjacent bunches align when the structure is assembled.

By virtue of the construction, therefore, continuous passages are afforded radially between the rings and laminations and around 90 the portions of the windings between the bunches of laminations, such passages extending from the space within the spider to the outer periphery of the rotor. Under the centrifugal action of the latter when running, continuous radial flow of air is maintained through these passages, the same exercising the desired cooling effect on the 95 rings, laminations and windings. By arranging the parts so that the spaces between 100 juxtaposed bunches of laminations are slightly narrower than the aligning spaces between the rings, a condition is created which makes for an increasing velocity of 105 air flow between the laminations with adequate supply between the rings to avoid detrimental back pressure.

The construction is especially advanta-

geous from the standpoint of manufacture and assembling, and particularly adapted to withstand the trying stresses of high speed operation.

5. What I claim is:

1. Rotor construction for electrical machines, comprising, in combination, a rotary support affording an air circulating space, rings embracing the same and spaced apart, bunches of laminations mounted on the rings with spaces between them in alignment with the spaces between rings and windings traversing the laminations.
2. Rotor construction for electrical machines, comprising, in combination, a rotary support affording an internal air circulating space, rings embracing the same and spaced apart, spacing members carried by the rings, and laminations retained on the rings and spacing members.
3. Rotor construction for electrical machines, comprising, in combination, a rotary frame having an internal air space, rings embracing the same and spaced apart to afford channels communicating with said air space, and laminations secured on the rings and spaced apart in alignment with said channels.
4. Rotor construction for electrical ma-

chines comprising a rotary frame having an 30 internal air space, rings encompassing the frame and spaced apart to afford air channels, spacing members between rings, said rings and spacing members having aligning lamination retaining parts, and laminations 35 retained by said parts.

5. Rotor construction for electrical machines comprising a rotary frame affording an internal air space, rings encircling the frame and spaced apart to afford air channels communicating with said space, bunches of laminations on the rings in staggered relationship, the bunches being spaced apart across the air channels, and spacing members 40 engaging the rings and laminations.

6. Rotor construction for electrical machines, comprising, in combination, a rotor frame affording an air space, rings encircling the same and spaced apart to afford air channels, bunches of laminations 45 retained on the rings and spaced apart to afford air passages aligning with said air channels, said air channels exceeding said air passages in width.

In testimony whereof I have hereunto 50 subscribed my name at Zurich, Switzerland, on the 11 day of January, A. D. 1926.

PHILIPP SUTER.
